TYPEWRITER ATTACHMENT

John E. Euth, Chicago, Ill., assignor to United
Autographic Register Co., a corporation of
Illinois

Application January 6, 1936, Serial No. 57,821

10 Claims. (Cl. 197—126)

This invention relates to typewriters adapted to fill in forms on continuous-form stationery, and more particularly to an improved device and method for holding carbon-slips interleaved with the stationery strips while the completed set of forms is advanced beyond the area served by the carbon-slips.

The primary object of the invention is to provide a carbon-holder which is slidably mounted in the rear of the platen, so as to move forwardly with the stationery; and to provide means for holding the carbon-holder in its remote or rear-most position with respect to the platen, to facilitate the transfer of the carbon from an advanced to a succeeding set of forms.

A further object of the invention is to provide an inexpensive and light device which is readily attachable to a standard type of machine when it is desired to use continuous-form stationery in the machine.

A further object of the invention is to provide an improved method of manipulating interleaved carbon-slips in continuous-form stationery.

The invention is illustrated in a preferred embodiment in the accompanying drawings, in which—

Fig. 1 is a side elevational view of the attachment, showing a platen roll and mounting means for the attachment, the typewriter being indicated by dotted lines; Fig. 2 a broken front elevational view of the attachment and stationery illustrated in Fig. 1; Fig. 3 a plan view of a carbon-holding blade showing a carbon-slip thereon and showing, brokenly, a shield for said carbon; Fig. 4 a broken plan view of one end of the blade shown in Fig. 3, with the carbon-slip unwrapped; Fig. 5 a front elevational view of the device shown in Fig. 2, with the stationery and carbon-slips removed; Fig. 6 a plan view of the housing frame for the wind-up drum, with the cover in raised position; Fig. 7 a broken sectional view taken as indicated at lines 7—7 of Fig. 8; Fig. 8 a sectional view taken as indicated at line 8 of Fig. 7; and Fig. 9 a broken sectional view showing a modified form of wind-up drum holding device.

In the embodiment illustrated, A designates a housing frame adapted to be detachably mounted on the shiftable platen carriage of a typewriter and equipped with a spring actuated wind-up roll A'; B a standard mounted on the housing frame and equipped at its remote end with a guide roller B'; C a carbon-slip holder; and D a fabric belt or curtain connecting the carbon-holder C to the wind-up drum A'.

The device is adapted for use on any standard

typewriter, as indicated by dotted lines in Fig. 1, the typewriter having the usual shiftable platen carriage, rotatable platen roll 10 and associated presser means, not shown, for feeding the paper into writing position. The standard platen carriage is equipped with a guard or apron 11, to which is bolted, or otherwise fastened, mounting hooks 12.

The housing frame A is shown in the form of a sheet metal canister provided with a cover 13, which is pivotally connected to the bottom of the housing at 14. The cover is provided with a downwardly extending flange 15, which is adapted to be engaged by screws 16 to hold the same in position. The front end of the canister is provided with strap brackets 17, which form sockets to receive the ends of the mounting hooks 12.

The wind-up drum A' is practically the same as an ordinary curtain rod drum and is supported in the frame by means of screws 18. The rod is hollow and is provided with a long suitably connected coil spring 19 to urge the drum to rotate in one direction. As shown in Figs. 6 and 7, one end of the drum is provided with a fixed head 20, in which is cut a deep thread to provide a helical slot 21. One end of the slot is provided with suitable stop means, such as a notch 22, see Fig. 8. The housing frame A' also contains a rock shaft 23, which is journaled on screws 24 and forms a sliding support for a pawl 25, which is non-rotatably mounted on the shaft. A spring 26 is provided to urge the pawl down into engagement with the slot 21, and one end of the shaft is provided with an operating lever 27 to enable the pawl to be lifted from engagement with the notch 22 at will. The standard B is rigidly connected to the housing frame A and is adjustable longitudinally by means of an expansion joint 28. The remote end of the standard is provided with a cross bar 29, equipped at its end portions with guide fingers 30, and serves to support the guide roller B'.

The carbon-holder C comprises a cross member 31, equipped at its end portions with slotted upwardly extending ears 32, which serve as keepers for the carbon supporting blades 33. The cross member 31 is further provided with guide members 34 for directing the stationery. The carbon blades 33 preferably are formed of thin, flat, resilient metal and have resilient integrally formed tongues 35, under which the carbon paper or shield may be inserted. The lateral end portions of the blades are provided with ears 36, which may be sprung into the keepers 32 of the carbon-holder C. As shown in Fig. 2, a

55

cross member 37 is provided to overlie the interleaved stationery strips and has ears 38 to engage the keepers 32. The member 37 is provided with a finger piece 39 to facilitate moving the carbon-holder as desired.

Preferably, the belt D is formed of a light, flexible fabric and is connected at one end to the rear portion of the carbon-holder C, as indicated at 40. The other end is attached to the wind-up roll A' in any suitable manner, so that the spring 19 is enabled to yieldingly draw the carbon-holder into its uppermost position, indicated in Fig. 1. As the belt is wide, the carbon-holder C' will remain at right angles to its line of travel as it slides up and down the frame B. When the spring is allowed to draw the carbon-holder to the uppermost position, the pawl 28 will drop into the notch 22 and prevent the carbon-holder from being drawn downwardly until the pawl has been raised by means of the lever 27. When the pawl is raised, there is usually sufficient tension in the belt D to prevent the pawl from reengaging the notch 22, and it is not necessary to start drawing the carbon-holder downwardly while holding the lever 27.

To load the machine for operation, the blades 33 are first provided with carbon-slips 41, and after the carbon has been folded over the rear edge of the blade, the edge portions of the carbon 30 may be inserted beneath the tongues 35. As shown in Figs. 2 and 3, the top blade may be provided with a shield 42, which extends downwardly a short distance with the carbon. The purpose of this shield will be described below. Continuous-form stationery 43, two strips being shown for the purpose of illustration, is draped over the guide roll B', and a carbon-slip interleaved there-in with the ears 36 sprung into the keepers 32. The stationery is then drawn down slightly beyond 40 the ends of the carbon-slips, the carbon-slips ending just short of the bight of the platen roll and presser means, and after releasing the carbon-holder by means of the lever 27, the loaded advanced set of forms is fed into writing position in the typewriter. The tension in the spring 45 18 is so adjusted that when the carbon-holder is released, the friction between the stationery and carbon is sufficient to draw it downwardly with the stationery. After a set of forms has been 50 filled in, the platen roll is backed up until the carbon-holder reaches its remote position and becomes automatically locked against downward movement by the action of the pawl 25 and the notch 22. The platen roll is then used to draw 55 the stationery forward, stripping it around the anchored carbon-slips, until the carbon shows through the register perforations 44, in the rear of the platen, as illustrated in Fig. 2. The shield 42 has sufficient length to prevent the carbon from 60 showing through the advancing register perforations until the stationery has been advanced sufficiently to properly load a succeeding set of forms, and thereby provides a very simple and accurate indicating device for this operation. The lever 65 27 is then depressed to release the carbon-holder, and the succeeding set of forms is then advanced into writing position. This operation will clear the completed set of forms sufficiently to permit them to be detached along their lines of weakening 45, provided between sets of forms.

In the modification illustrated in Fig. 9, instead of employing an automatic stop device, a friction clutch or gripping device is provided, which enables the wind-up drum 46 to be locked at any desired position. The drum is provided with a

spring 47 and fabric belt 48, which operates in the same way as the device described above. However, one end of the drum is provided with a clutch face 49 and a trunnion 50, the latter being adapted to slide in a recess 51, provided in the center of a shiftable clutch face 52. The shiftable portion of the clutch is carried in a hollow boss 53, which is recessed, as indicated at 54, to receive a spring 55, which urges the clutch face 52 into engagement with the drum face 49. The outer end of the boss 53 is provided with a cam slot 56, which is adapted to be engaged by a detent 57, carried by operating lever 58, which is fixed to the movable portion of the clutch by means of a screw 59. Thus, it will be understood that by moving the lever 58, the clutch faces will be separated, and the drum is free to rotate. The device is used in the same manner as described above, except that when the carbon-holder reaches its uppermost position on the frame B, it is necessary to lock the drum by means of the handle 58, rather than by the automatic means provided in the preferred embodiment.

The foregoing detailed description is given for clearness of understanding only, and no unnecessary limitations should be understood therefrom, but the appended claims should be construed as broadly as permissible in view of the prior art. 25

I claim;

1. In a typewriter having a carriage with a platen roll around which stationery strips interleaved with transfer-slips may be led: a frame mounted on said carriage; a transfer-slip holder slidably mounted on said frame for movement to and from said platen roll; spring means for automatically moving said holder away when the platen roll is turned rearwardly; means for locking said holder in a position remote from said platen; and manual means adjacent to said platen roll for releasing said locking means. 10 20 30

2. A device as specified in claim 1, in which the frame is equipped with a guide roll at its end remote from the platen, and the spring means comprises a spring actuated wind-up drum adjacent to the platen and connected to the transfer-slip holder by means of a belt passing over said guide roll. 45

3. A device as specified in claim 1, in which the locking means automatically holds the carbon holder when the latter reaches its remote position on the frame. 50

4. In a typewriter having a carriage with a platen roll around which stationery strips interleaved with transfer-slips may be led: a spring actuated wind-up drum of the curtain roll type rotatably mounted on said carriage near said platen roll and adapted to draw yieldingly an associated transfer-slip holder away from said platen; a gripping device at one end of said drum adapted to engage said drum and prevent its rotation; and manually operable lever means for releasing said gripping device.

5. A device as specified in claim 4, in which the gripping device comprises a friction clutch having a slidible head recessed to receive a trunnion provided on the wind-up drum, and the lever means includes cam means for drawing the shiftable head axially away from said drum. 65

able head axially away from said drum.
6. In a device of the character set forth: a frame in which is journalled a wind-up drum; spring means urging rotation of said drum in but one direction; a worm at one end of said drum affording a helical slot provided near one end with stop means; and a detent movably mounted adjacent to said drum and adapted to travel in

said slot and engage said stop means so as to prevent backward rotation of the drum.

7. In a device of the character set forth: a frame in which is journalled a wind-up drum; spring means urging rotation of said drum in but one direction; a worm at one end of said drum affording a helical slot provided near one end with stop means; a shaft journalled in said frame adjacent to said drum; a pawl member slidably mounted on said shaft and having a detent adapted to travel in said slot and engage said stop means to restrain rotation of the drum in a backward direction; and manually operable means for raising said detent from engagement with the stop means.

8. In a device of the character set forth: a frame in which is journalled a wind-up drum; spring means urging rotation of said drum in but one direction; a worm at one end of said drum affording a helical slot provided near one end with a notch; a rock shaft journalled in said frame adjacent to said drum; a pawl member non-rotatably mounted on said rock shaft for axial sliding movement thereon, said pawl member having a detent adapted to travel in said slot and engage in said notch to prevent backward rotation of the drum; spring means on said rock shaft for urging said detent into engagement with the slot; and a lever on the shaft for lifting the detent from engagement with the stop means.

9. In combination with a typewriter having a shiftable carriage provided with a platen roll; mounting means secured to said carriage; a hous-

ing frame having means for detachably engaging said mounting means; a spring actuated wind-up drum journalled in said housing and having at one end a helical slot provided with stop means; a detent pivotally mounted in said housing frame 5 to travel in said slot and engage said stop means; manually operable means for releasing said detent from the stop means; a standard mounted on said housing frame and extending upwardly and rearwardly from the platen; a guide roller and 10 guide fingers provided at the remote end of said standard; a carbon-holder adapted to slide on said standard and to hold carbon-slips in interleaved relation with stationery strips led over the guide roller to said platen; and a fabric belt 15 passing over the guide roller and connecting the carbon-holder to said wind-up drum.

10. In a typewriter having a carriage with a platen roll around which stationery strips interleaved with transfer-slips may be led: a frame 20 mounted on said carriage; a transfer-slip holder slidably mounted on said frame for movement to and from said platen roll, said transfer-slip holder having at each lateral end-portion a blade keeper, and a thin resilient blade having unitary 25 spring tongues for engaging the transfer-slips and having at its ends outwardly extending ears for engaging said keepers; means for moving said holder away from the platen; means for locking said holder remote from the platen; and means 30 for releasing said locking means.

JOHN E. EUTH.
